CLAIM

The ornamental design for a display screen or portion thereof with graphical user interface as shown and described.

DESCRIPTION

FIG. 1 is a front view of a display screen or portion thereof with graphical user interface showing our new design.

FIG. 2 is a second embodiment thereof; and,

FIG. 3 is a third embodiment thereof.

The outermost dot dashed lines in the Figures show a display screen or portion thereof and form no part of the claimed design. The other broken lines shown in the Figures show portions of the graphical user interface that form no part of the claimed design. The grayscale shows a contrast in appearance.
